(57) **CLAIM**

The ornamental design for an electronic device, as shown and described.

DESCRIPTION

FIG. 1 is a top, front perspective view of a first embodiment of an electronic device showing our new design;

FIG. 2 is a top, rear perspective view thereof;

FIG. 3 is a bottom, front perspective view thereof;

FIG. 4 is a bottom, rear perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof;

FIG. 11 is a top, front perspective view of a second embodiment thereof;

FIG. 12 is a top, rear perspective view thereof;

FIG. 13 is a bottom, front perspective view thereof;

FIG. 14 is a bottom, rear perspective view thereof;

FIG. 15 is a front view thereof;

FIG. 16 is a rear view thereof; FIG. 17 is a left side view thereof;

FIG. 18 is a right side view thereof;

FIG. 19 is a top view thereof; and,

FIG. 20 is a bottom view thereof.

The dashed broken lines are for the purpose of illustrating portions of the electronic device and form no part of the claimed design.

The relatively light gray shade lines on the surface portions of FIGS. 1-10, and the relatively thin black shade lines on the surface portions of FIGS. 11-20 indicate contour and not surface decoration.

The gray shading on a portion of the electronic device in FIGS. 11-20 represents a metallic surface.
